UNITED STATES PATENT OFFICE

JOHN A. HELLER, OF CARTHAGE, MISSOURI

COIN CONTROL MECHANISM FOR VENDING MACHINES

Application filed March 23, 1931. Serial No. 524,726.

This invention relates to certain new and useful improvements in coin control mechanism for vending machines.

The primary object of the invention is to provide a coin control mechanism for vending machines or apparatus of the character described in application filed by John A. Heller on March 23, 1931, Serial Number 524,725, and in which it is required that a coin be deposited to effect release of the operating mechanism for the dispensing of an article.

A further object of the invention is to provide coin control mechanism for vending machines wherein an operating plunger for the vending mechanism is restrained from operation until a coin of the proper denomination is inserted in the coin control mechanism which includes a magnet for the extraction of a magnetic plug and also a coin ejector for a slug having a central opening therein, such as a metallic washer.

A still further object of the invention is to provide coin control mechanism for vending machines wherein a slug that is off size in diameter relative to a coin of proper denomination for the operation of the mechanism, either plus or minus as little as .002 inch or more will be ineffective in the release of the mechanism for the operation of the vending apparatus.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a detail sectional view showing a mounting plate for the coin control mechanism of a vending machine with the manually shiftable rod for operating the vending mechanism, the manually shiftable rod being shown at its limit of inward movement;

Figure 2 is a detail sectional view, similar to Figure 1, showing the shiftable rod moved to its limit of outward movement;

Figure 3 is a fragmentary elevational view

of a part of the rod with a latch lever engaged therewith, showing the rod in partially withdrawn position;

Figure 4 is a detail elevational view, similar to Figure 3, showing the shiftable rod in its partially projected position;

Figure 5 is a fragmentary elevational view, partly in section, showing a coin by dotted lines, at the point of entering the mechanism, a coin illustrated by full lines in position to permit operation of the coin control mechanism and a third coin illustrated by full lines, restrained by a temporary stop;

Figure 6 is a fragmentary elevational view, partly in section, similar to Figure 5, showing the operating rod in its shifted position for the operation of the vending mechanism, the second coin released from its point of rest and the third coin restrained by the temporary stop discharged for reception in a collection box;

Figure 7 is a top plan view of a manually shiftable rod for operating the vending mechanism;

Figure 8 is a perspective view of the lock arm controlling the operation of the manually shiftable rod;

Figure 9 is a cross-sectional view taken on line 9-9 of Figure 7;

Figure 10 is a cross-sectional view taken on line 10-10 of Figure 7;

Figure 11 is a cross-sectional view taken on line 11-11 of Figure 7;

Figure 12 is a fragmentary elevational view, similar to Figures 5 and 6 showing the direction of travel of coins of proper denominations, through the mechanism, and the direction of travel of magnetic slugs;

Figure 13 is an edge elevational view of the coin control mechanism showing the manually shiftable rod projecting through;

Figure 14 is a rear elevational view of the mechanism shown in Figure 12, better to illustrate the tensioned lock arm for the rod;

Figure 15 is a detail view showing the coin plunger and coin ejector with a coin illustrated in section with the latter disposed for operation by the plunger;

Figure 16 is a detail view showing the

plunger moved into engagement with the coin;

Figure 17 is a detail view showing the ejector engaged in the center opening of a slug; 5 and

Figure 18 shows the ejector engaged with the bottom wall of the slug opening with the plunger spaced from the slug.

The coin control mechanism disclosed 10 herein being primarily intended for association with the dispensing apparatus for bottled beverages described in application filed by John A. Heller and co-pending here-with, it is intended that the mounting plate 15 for the coin control mechanism as shown in Figures 1 and 4, may represent a front wall 1 of a refrigerant casing. A manually shift-able plunger rod comprising sections 65 and 65a with an intermediate annularly reduced 20 portion 2 is slidable through the casing wall 1, being guided in a sleeve 3 projecting out-wardly of the casing wall, the outer end of the rod section 65a being provided with a handle 75 to facilitate operation thereof. 25 The sleeve 3 is carried by a frame at the inner side of the casing wall 1 and said frame, as shown in Figures 1 and 2, comprises a pair of spaced parallel walls 4 and 5 connected by a head block 6 from which a brack- 30 et 7 projects and upon the outer end of which bracket a latch dog 8 is pivotally mounted as at 9. The inner end section 65 of the man- 35 ually shiftable rod is provided with a cross opening 10 from which a pin 64 shown in Figure 7 projects for engagement with the vending mechanism within the casing.

The manually shiftable rod as shown in Figures 1 to 4 and 7, has a shoulder 11 at the end of the section 65 adjacent the an- 40 nularly reduced portion 2, while the upper side of the rod section 65 adjacent the shoul- 45 der 11 is provided with a series of ratchet notches 12 and a pocket 13 at the inner end of the ratchet notches. One side of the shaft 50 section 65a is vertically cut away at an angle to provide a side recess 14 having inclined side walls 15 forming cam surfaces for pur- 55 poses presently to appear. When the rod is entirely projected into the casing, the ratch- 60 et dog 8 is directed toward the annularly re- 65 duced portion 2 of the rod and is spaced therefrom to permit outward movement of the rod as illustrated in Figure 3, the ratch- 70 et dog 8 moving over the ratchet notches 12 and being engaged therewith as illustrated 75 in Figure 3, necessitating full retraction or a pull upon the operating rod to position the ratchet dog 8 in the pocket 13 as shown in Figure 2, and at which time the operating 80 rod may be returned or projected into the casing with the dog 8 ratcheting over the notches 12 as shown in Figure 4, it being necessary that the rod be completely projected into the casing before the same can 85 again be retracted.

A lock arm that is coin controlled in its operation is associated with the manually shiftable rod, the same being shown in detail in Figure 8, the lock arm 16 having a trans- 90 versely extending arcuate slot 17 therein to facilitate pivotal mounting upon the wall 4 by the screw pin 18, the upper end of the through of the rod section 65, the opening 19 therein received on the operating rod and being of a diameter to permit passage there- 95 through of the rod section 65, the opening 19 in the lock arm normally surrounding the annularly reduced portion 2 of the chair while said lock arm is moved on its pivot 18 under influence of the spring 20 for posi- 100 tioning the opening 19 out of alinement with the shoulder 11 on one end of the rod section 65 to prevent movement of the rod section 65 through the lock lever opening, this offset position being clearly shown in Figure 14. A cylindrical block 21 projects laterally from the lower end of the lock arm 16 in a direc- 105 tion toward the frame wall 5 and an abut- 110 ment shoulder 22 is formed at the outer end of the block 21 to be engaged by a coin for moving the lock arm on its pivot 18 to aline the opening 19 in the upper end thereof with the shoulder 11 and rod section 65 to permit passage of the rod section through the lock arm opening, this operation to be later de- 115 scribed.

A plunger blade 23 is vertically slidable within the frame, being guided in its move- 120 ment through a slot 24 provided in the frame wall 5, the upper end of the plunger blade 23 being bevelled as at 25 and adapted to enter the cut-away portion 14 in the rod section 65a for engagement with the adjacent cam wall or surface 15 as shown in Figure 1. A coin ejector 26 pivotally depends from the lower edge of the plunger blade 23 as at 27 adjacent the casing wall 1, it being noted from an inspection of Figures 1 and 2 that the frame wall 5 is spaced from the casing wall 1 providing a passageway for a coin. A coin stop 28 in the form of a plate has an angle finger 29 at its upper end supported on the bottom wall of the guide slot 24 in the wall 5 for the plunger blade 23, the bottom wall of the slot 24 being inclined as at 30 to permit free pivotal movement of the stop 28, the lower end of the stop carrying an angle arm 31 normally positioned beneath the lower end of the wall 5 to close the lower end of the passageway 32 for a coin.

A coin is inserted through an opening in the casing wall 1 and travels in a downward direction over an inclined magnet 34 and should said coin be a magnetic slug, or a slug possessing magnetic attractions, the same will follow the magnet 34 and be discharged from the apparatus as shown at 35 in Figure 12. If the coin is of the proper denomina- 125 tion, the same will travel downwardly through the coin passage 32 as indicated by 130

dotted line positions 36 and 37 in Figure 12 and temporarily brought to rest by contact with the abutment shoulder 22 on the block 21 carried by the lock arm 16 and an abutment 38 shown in Figures 5, 6 and 12 to occupy the position shown at 39. The lock arm 16 is slightly shifted on its pivot 18 when the coin moves into engagement therewith as shown at 39 and said coin in this position is directly beneath the plunger blade 23. The operating rod is then shifted by the handle 75, rotation thereof being prevented by a key entering the longitudinal key way 40 in the side of the rod section 65, the cam surface 15 forming an end wall of the cut away portion 14 working upon the inclined upper edge 25 of the plunger blade for lowering the same against the tension of one end of the spring 20 as shown in Figure 6, the plunger blade 23 shifting the coin from the temporary support on the abutment 38 and abutment shoulder 22 and correctly aligning the opening 19 in the lock arm with the shoulder 11 of the rod section 65, permitting complete retraction 25 of the operating rod to the position shown in Figure 2. During downward movement of the plunger blade 23, the same is engaged with the coin 39 as shown in Figure 16, the coin 39 being then in the position shown at 41 in Figure 6 for engagement with the angle finger 29 upon the coin stop 28 for shifting the coin stop from the position shown in Figure 1 to that shown in Figure 2, whereby a previously deposited coin shown at 42 in Figure 5 is permitted to escape as at 43 in Figure 6 for reception in a coin box or the like, the coin stop 28 gravitationally closing for catching and retaining the next coin passing through the passageway from the position 41. In the event of a slug being introduced into the mechanism that is not of the exact diameter of the proper denomination of coin for working the apparatus, the lock arm 16 will be shifted a too greater or 45 too lesser distance to position the opening 19 therein for the passage of the rod section 65. In the event of a slug being introduced into the machine, such as a metallic washer of non-magnetic metal, but of the exact diameter of a coin of proper denomination, the washer slug will occupy the position shown at 39 in Figure 5 and the ejector 26 which moves over a side face of a coin of proper denomination will engage in the center opening 44 of the washer slug 45 as shown in Figure 17. By operating the rod by the handle 75, the plunger blade 23 is lowered and is engaged with the bottom side of the opening 44 as shown in Figure 18, always 50 keeping the washer slug 45 spaced from the plunger blade 23, such movement causing aligning of the opening 19 in the lock arm with the shoulder 11 upon the rod section 65, but as soon as the washer slug has been carried beyond the point 39, the spring 20 oper-

ates to shift the lock arm 16 and displace the opening 19 out of alignment with the rod shoulder 11, before the shoulder reaches the opening in the lock arm. The coin ejector 26 therefore prevents operation of the coin mechanism and more particularly the operating rod when an apertured slug is inserted in the machine. 70

From the above detailed description of the mechanism, it is believed that the construction and operation thereof in conjunction with vending apparatus will at once be understood, it being noted that the guard arm 46 pivoted on the frame as at 47 has suitable devices associated therewith for causing the arm to drop to the dotted line position shown in Figure 6 to overlie the coin receiving opening when the drum with which the particular coin opening is associated is empty and while there is herein shown and described the preferred embodiment of the invention, it is nevertheless to be understood that minor changes may be made therein without departing from the spirit and scope of the invention as claimed. 90

I claim:—

1. In coin control mechanism of the character described, a manually reciprocable rod for operating vending mechanism, said rod having a reduced portion defining a shoulder on the rod, a pivoted lock arm having an opening therein received on the reduced portion of the shaft and normally positioned to place the rod shoulder out of alignment with the arm opening, the arm providing a temporary support for a coin inserted in the mechanism, and means operated by the rod for moving the coin through the mechanism, and shifting the lock arm to align the arm opening with the rod shoulder to permit reciprocating movement of the rod. 100

2. In coin control mechanism of the character described, a manually shiftable rod for operating vending mechanism, a coin controlled lock arm associated with the rod for controlling operation thereof, coin moving means operated by the rod for moving the lock arm to position to permit movement of the rod, the coin moving means including a slidable plunger having a bevelled upper end and said rod having a cut away portion into which the bevelled end of the plunger is received, and a cam wall for the recess engaged with the plunger bevel for operating the plunger during reciprocation of the rod. 110

3. In coin control mechanism of the character described, a manually shiftable rod for operating vending mechanism, a coin controlled lock arm associated with the rod for controlling operation thereof, means associated with the rod necessitating complete movements in either direction before the rod can be reversed in movement, coin moving means operated by the rod for moving the lock arm to position to permit movement 125

of the rod, the coin moving means including a slideable plunger having a bevelled upper end and said rod having a cut away portion into which the bevelled end of the plunger is received, and a cam wall for the recess engaged with the plunger bevel for operating the plunger during reciprocation of the rod.

4. In coin control mechanism of the character described, a manually reciprocable rod 10 for operating vending mechanism, said rod having a reduced portion defining a shoulder on the rod, a pivoted lock arm having an opening therein received on the reduced portion of the shaft and normally positioned to place the rod shoulder out of alinement with the arm opening, the arm providing a temporary support for a coin inserted in the mechanism, means operated by the rod for moving the coin through the mechanism, and 15 shifting the lock arm to aline the arm opening with the rod shoulder to permit reciprocating movement of the rod, the coin moving means including a slideable plunger having a cut away portion into which the bevelled end 20 of the plunger is received, and a cam wall for the recess engaged with the plunger bevel for operating the plunger during reciprocation of the rod.

5. In coin control mechanism of the character described, a manually shiftable rod for operating vending mechanism, a coin controlled lock arm associated with the rod for controlling operation thereof, coin moving means operated by the rod for moving the lock arm to position to permit movement of the rod, the coin moving means including a slideable plunger having a bevelled upper end and said rod having a cut away portion into which the bevelled end of the plunger is received, a cam wall for the recess engaged with the plunger bevel for operating the plunger during reciprocation of the rod, and a coin ejector pivotally depending from the slideable plunger for holding an apertured slug in advance of the plunger.

6. In coin control mechanism of the character described, a manually shiftable rod for operating vending mechanism, a coin controlled lock arm associated with the rod for controlling operation thereof, means associated with the rod necessitating complete movements in either direction before the rod can be reversed in movement, coin moving means operated by the rod for moving the lock arm in position to permit movement of the rod, the coin moving means including a slideable plunger having a bevelled upper end and said rod having a cut away portion into which the bevelled end of the plunger is received, a cam wall for the recess engaged with the plunger bevel for operating the plunger during reciprocation of the rod, and a coin ejector pivotally depending from the slideable plunger for holding an apertured slug in advance of the plunger.

7. In coin control mechanism of the character described, a manually reciprocable rod for operating vending mechanism, said rod having a reduced portion defining a shoulder on the rod, a pivoted lock arm having an opening therein received on the reduced portion of the shaft and normally positioned to place the rod shoulder out of alinement with the arm opening, the arm providing a temporary support for a coin inserted in the mechanism, means operated by the rod for moving the coin through the mechanism, and shifting the lock arm to aline the arm opening with the rod shoulder to permit reciprocating movement of the rod, the coin moving means including a slideable plunger having a cut away portion into which the bevelled end of the plunger is received, a cam wall for the recess engaged with the plunger bevel for operating the plunger during reciprocation of the rod, and a coin ejector pivotally depending from the slideable plunger for holding an apertured slug in advance of the plunger.

8. In coin control mechanism of the character described, a manually shiftable rod for operating vending mechanism, a coin controlled lock arm associated with the rod for controlling operation thereof, coin moving means operated by the rod for moving the lock arm to position to permit movement of the rod, the coin moving means including a slideable plunger having a bevelled upper end and said rod having a cut away portion into which the bevelled end of the plunger is received, a cam wall for the recess engaged with the plunger bevel for operating the plunger during reciprocation of the rod, a coin ejector pivotally depending from the slideable plunger for holding an apertured slug in advance of the plunger, and a spring engaged with the lock arm for moving the same to a position to prevent movement of the rod after a coin has passed in contact with the rod.

9. In coin control mechanism of the character described, a manually shiftable rod for operating vending mechanism, a coin controlled lock arm associated with the rod for controlling operation thereof, means associated with the rod necessitating complete movements in either direction before the rod can be reversed in movement, coin moving means operated by the rod for moving the lock arm in position to permit movement of the rod, the coin moving means including a slideable plunger having a bevelled upper end and said rod having a cut away portion into which the bevelled end of the plunger is received, a cam wall for the recess engaged with the plunger bevel for operating the plunger during reciprocation of the rod, a coin ejector pivotally depending from the slideable plunger for holding an apertured slug in advance of the plunger, and a spring

engaged with the lock arm for moving the same to a position to prevent movement of the rod after a coin has passed in contact with the rod.

10. In coin control mechanism of the character described, a manually reciprocal rod for operating vending mechanism, said rod having a reduced portion defining a shoulder on the rod, a pivoted lock arm having an opening therein received on the reduced portion of the shaft and normally positioned to place the rod shoulder out of alignment with the arm opening, the arm providing a temporary support for a coin inserted in the mechanism, means operated by the rod for moving the coin through the mechanism, and shifting the lock arm to align the arm opening with the rod shoulder to permit reciprocating movement of the rod, the coin moving means including a slidable plunger having a cut away portion into which the bevelled end of the plunger is received, a cam wall for the recess engaged with the plunger bevel for operating the plunger during reciprocation of the rod, a coin ejector pivotally depending from the slidable plunger for holding an apertured slug in advance of the plunger, and a spring engaged with the lock arm for moving the same to a position to prevent movement of the rod after a coin has passed in contact with the rod.

In testimony whereof I affix my signature.
JOHN A. HELLER.
